CHIROPRACTIC TREATMENT TABLE

Barry M. Blumberg, Chatsworth, Calif., assignor to BAC
Industries, Inc., Chatsworth, Calif.

Filed Oct. 18, 1974, Ser. No. 516,011

Term of patent 14 years

Int. Cl. D24—01

U.S. Cl. D83—1 D

FIG. 2

FIG. 1 is a perspective view of a chiropractic treatment table, showing my new design; and

FIG. 2 is a perspective view thereof showing the side and end opposite to that shown in FIG. 1.

I claim:

The ornamental design for a chiropractic treatment table, substantially as shown.
